UNITED STATES PATENT OFFICE

2,450,762

RING

Clinton E. Marshall, Bronx, N. Y.

Application June 20, 1945, Serial No. 600,465

8 Claims.

(CL. 63—15)

1

This invention relates to finger rings. More particularly, the invention deals with devices of this class having a dual ring structure, whereby a jeweled or otherwise characterized member may be detachably coupled with respect to a substantially plain ring member, thereby providing two distinct uses of the ring structure and, particularly, in adapting jeweled mountings to a plain or unjeweled wedding ring.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a side view of a ring made according to my invention on an enlarged scale with part of the construction broken away and in section.

Fig. 2 is an enlarged sectional view on the line 2—2 of Fig. 1 with part of the construction broken away; and

Fig. 3 is a plan view of the inner surface of the outer jeweled ring member, as viewed substantially on the line 3—3 of Fig. 2.

In recent years, the trend has been to incorporate with wedding rings mountings for jewels of various kinds and classes, which jewels have become a permanent part of the ring structure and, if the wedding ring is kept upon the hand, the jeweled ring is exposed to wear and tear, to which the hand may be subjected.

As an alternative, jeweled rings of this type and kind have been removed from the hand in order to save wear and avoid destruction thereto. This latter procedure, however, has been objectionable to some owners superstitious with regard to removal of a wedding ring from the finger of the hand.

It is the purpose of my invention to provide a simple and practical construction, wherein the wedding ring proper may be at all times maintained on the hand and a jeweled section or member removed from the main ring as and when required by forcible detachment and, in like manner, forcibly replaced on the main ring when it is desirable to display the jeweled characteristics of the complete ring assemblage.

In illustrating one adaptation and use of my invention, I have shown in the accompanying drawing a main ring 5, which may be of more or less standard wedding ring construction, except for the formation of two circumferential recesses or depressions 6 and 7 in the outer surface of the ring adjacent side edges thereof. The slight depressions 6 and 7 are joined by an intermediate slightly domed portion 8, which extends from

the base of the recesses 6 and 7 to the center portion of the ring. The recesses 6 and 7 join the outer side edge portions of the ring in abruptly bevelled wall portions 9 and 10, which form 5 retainer wall portions engaged by spring members or fingers 11, 11' formed from and extending inwardly from the inner, annular wall portion 12 of an outer jewel mounting ring member 13. The particular manner of constructing 10 the member 13 is of no specific importance, as it may be formed from a single band of material or of several parts suitably secured together. However, it is desirable that the member includes the inner wall portion 12 and an outer wall portion 14, in which are provided suitable 15 mountings 15 for jewels 16 of any type or kind. The jewels may extend throughout the complete circumference of the member 13 or be disposed over part only of the circumference, as illustrated 20 in Fig. 1 of the drawing. The wall 14 joins the wall 12 in side wall portions 17 and 18. In the construction shown, three pairs of the spring members 11, 11' are arranged at circumferentially spaced intervals on the wall 12.

25 The outwardly flared substantially hook-shaped ends 19, 19' of the springs 11, 11' are adapted to ride freely over the rounded outer corners 20, 20' of the main ring 5 in moving the ring 13 on the ring member 5; when arranged in assembled and 30 alined position, the spring members 11, 11' will snap into the recesses 6 and 7 with the hook ends 19, 19' engaging the walls 9 and 10 retaining the ring member 13 against accidental transverse displacement on the ring member 5. However, by 35 applying force, the ring member 13 may be withdrawn from the ring member 5, in which operation the hook ends 19, 19' will ride over one of the walls 9—10 and above the dome portion 8; for example, in displacing the member 13 to the 40 left, as seen in Fig. 2, the hook end 19 will ride over the wall 6; whereas the hook end 19' will ride over the dome portion 8 and then over the wall 6. It will be understood that the illustrations in the accompanying drawing are exaggerated as to size and are somewhat diagrammatically shown, but nevertheless demonstrates the principle of providing on a pair of interfitting ring members means for retaining said ring members against accidental displacement, while providing for detachment or separation thereof for 45 purposes hereinbefore stated.

The principles of this invention are applicable to jewelry of any type and kind where it is desirable to remove jeweled or characterized portions from a surface of the jewelry. As a further example, it may be said that the member 5 may comprise a base mounting, upon which ring

structures of different types and kinds can be arranged. In other words, the member 13 may comprise one of a number of members detachable with a single body 5 having a common or substantially common means for retaining the member 13 against displacement from the member 5. Here the member 13 can have different shapes and contours and different types and kinds of ornamentations, jewels, etc., and in different arrangements, that is to say, the invention is not necessarily limited to adaptations for use on wedding ring bases, but would provide a base ring mounting that may be used with several different types and kinds of characterized ring members.

It will be also apparent that, in dual ring structures of the type and kind under consideration, the inner or so-called base ring structure, such as the member 5, may be utilized, within limits, as a means for controlling size in adapting a ring to fit fingers of varying sizes, so that, in the sale of a ring section, such as a section or member 13, a storekeeper may insert a member 5 of a size to fit the finger of a hand. In other words, the member 5 may be considered as a size adaptor member.

Having fully described my invention, what I claim as new and desire to secure by Letters Patent is:

1. In a wedding ring structure, an inner circumferentially continuous main ring member, an outer circumferential continuous characterized ring member and interengaging means on said members for retaining the same against accidental displacement while permitting forcible separation one from the other, said last named means comprising a groove portion on the main ring member inwardly of side edges thereof, and circumferentially spaced yieldable portions on the other member within side edges thereof adapted to enter the groove portion of the main ring member.

2. In a wedding ring structure, an inner main ring member, an outer characterized ring member and interengaging means on said members for retaining the same against accidental displacement while permitting forcible separation one from the other, said last named means comprising a groove portion on one member, yieldable portions on the other member adapted to enter the groove portion of the first member, said means comprising annular grooves on the surface of the main member adjacent side edges thereof, and inwardly extending springs on the inner surface of the outer member engaging the grooves of said inner member.

3. In a wedding ring structure, an inner main ring member, an outer characterized ring member and interengaging means on said members for retaining the same against accidental displacement while permitting forcible separation one from the other, said last named means comprising a groove portion on one member, yieldable portions on the other member adapted to enter the groove portion of the first member, said means comprising annular grooves on the surface of the main member adjacent side edges thereof, inwardly extending springs on the inner surface of the outer member engaging the grooves of said inner member, and the grooves of said inner member being joined by an intermediate dome portion.

4. In a wedding ring structure, an inner main ring member, an outer characterized ring member and interengaging means on said members for

retaining the same against accidental displacement while permitting forcible separation one from the other, said last named means comprising a groove portion on one member, yieldable portions on the other member adapted to enter the groove portion of the first member, said means comprising annular grooves on the surface of the main member adjacent side edges thereof, inwardly extending springs on the inner surface of the outer member engaging the grooves of said inner member, the grooves of said inner member being joined by an intermediate dome portion, and said grooves having outer abruptly bevelled wall portions.

5. In a wedding ring structure, an inner main ring member, an outer characterized ring member and interengaging means on said members for retaining the same against accidental displacement while permitting forcible separation one from the other, said last named means comprising a groove portion on one member, yieldable portions on the other member adapted to enter the groove portion of the first member, said means comprising annular grooves on the surface of the main member adjacent side edges thereof, inwardly extending springs on the inner surface of the outer member engaging the grooves of said inner member, the grooves of said inner member being joined by an intermediate dome portion, and the springs of the outer member being arranged in pairs and being spaced circumferentially of said outer member.

6. A ring member comprising an outer characterized wall portion, an inner annular wall portion, said inner annular wall portion having circumferentially spaced and inwardly extending mounting springs adapting said ring member for mounting on a supporting base.

7. The combination with a base ring having a bore adapted to fit the finger of a hand, of a circumferentially continuous characterized ring adapted for detachable mounting on the base ring, interengaging means comprising circumferentially spaced yieldable elements arranged with in and spaced from side edges of the combined ring structure for coupling the characterized ring with said base ring, the base ring having a recessed outer surface, and said elements being disposed on the inner surface of the characterized ring.

8. In jewelry of the character described, the combination with a circumferential base ring having a circumferential groove on the outer surface and inwardly of side edges thereof, of a characterized ring adapted for mounting on said base ring, and said characterized ring having on the inner surface thereof circumferentially spaced yieldable elements arranged inwardly of side edges of said ring and adapted to engage the groove of said base ring in detachably mounting the characterized ring on said base ring.
